Patented Aug. 10, 1926.

UNITED STATES PATENT OFFICE.

WADE H. HARRISON, OF PETERSBURG, VIRGINIA.

GARMENT-HANGER-SUPPORTING MECHANISM FOR WARDROBE TRUNKS.

Application filed March 25, 1925. Serial No. 18,174.

The present invention appertains to a garment hanger supporting mechanism, adapted particularly for use in wardrobe trunks, and an important object of the invention is to provide a mechanism of this nature, which may be easily and quickly lifted out of the wardrobe trunk and supported in a closet or the like.

Another important object of the invention is to provide a mechanism of this nature having adjustable arms so that the length thereof may be varied as desired.

A further object of the invention is to provide efficient means for supporting the mechanism in a trunk.

A still further object of the invention is to improve upon mechanisms of this nature by providing one possessed of an exceedingly simple structure, which may be manufactured at a comparatively low cost, one which is efficient and reliable in use, strong, durable, not liable to readily get out of order, and otherwise well adapted to the purpose for which it is designed.

With the above and numerous other objects in view, as will appear as the description proceeds, the invention resides in certain novel features of construction, and in the combination and arrangement of parts, as will be hereinafter more fully described and claimed.

In the drawing:

Figure 1 is a fragmentary horizontal section, through a trunk, showing my improved garment hanger supporting mechanism mounted therein.

Figure 2 is a vertical section taken therethrough, and

Figure 3 is a perspective view of the mechanism showing the manner in which the same may be supported in a closet, on the wall or the like.

Referring to the drawing in detail, it will be seen that a trunk has been indicated generally by the letter A and includes among other elements the end walls 5 and side walls 6. A strap 7 is fixed to one side wall 6 and has extensions 8 fixed to the end walls 5. The intermediate portion of this strap 7 which is fixed to the side wall 6 is provided with a pair of spaced brackets 9 having the pockets therein. Brackets 10 are fixed to the extensions 8 and are substantially L-shaped in formation, the upper ends thereof being reduced as at 11.

My improved garment hanger supporting

mechanism per se is indicated generally by the letter B. Referring particularly to this mechanism, it will be seen that the numeral 12 indicates the supporting bar, having three depending fingers 13, one at each end thereof, and one at the center thereof. These end fingers 13 are adapted to be received in the pockets of the brackets 9, as is indicated to advantage in Figure 2, whereby the mechanism may be supported in the trunk. The center finger 13 is adapted to be received in a pocket bracket 9', supported on a wall in a closet or the like, so that the mechanism may be mounted therein when desired. A pair of arms C project perpendicularly from the ends of the bar 12, so as to extend parallel with the end walls 5 of the trunk, when the mechanism is supported therein. The arms C each include an inner fixed rod 15 and an outer tubular rod 16, slidable over the rod 15. The rod 16 is provided with a longitudinally extending slot 17. The rod 15, adjacent its end is provided with a pocket 18, for the reception of the adjacent reduced end 11 of bracket 10. A stop pin 19 projects from the rod 15 adjacent the pocket 18 and extends through the slot 17, thereby limiting the outward sliding movement of the tubular rod 16. A stop lug 20 is formed on the end 85 of the rod 16 and extends upwardly and perpendicularly therefrom. A trolley bar 21 is provided with hooked ends 22, for engagement over the arms C. The stop lugs 20 prevent this trolley bar from slipping off 90 of the arms C.

It will be apparent from the above that I have set forth a highly efficient embodiment of my improved garment hanger supporting mechanism which may be mounted 95 in a secure manner, in a wardrobe trunk or the like, and that this embodiment attains all of the features of advantage enumerated as desirable in the statement of the invention and the above description.

It is desired, however, to point out that numerous changes in the details of construction and in the combination and arrangement of parts may be resorted to, without departing from the spirit or scope of the invention, as hereinafter claimed, or sacrificing any of its advantages.

Having thus described my invention, what I claim as new is:

In combination, a supporting strap of U-shaped formation including an intermediate portion and side extensions, pocket brackets

mounted on the intermediate portion of the thereof, each arm including an inner fixed 10 supporting strap in spaced relation adjacent rod, and an outer tubular rod slidable on the the end extension, L-shaped brackets mounted on the end extensions of the strap and 5 fixed rod, each tubular rod provided with terminating in reduced terminals, a supporting bar provided adjacent its ends with depending fingers adapted to be received in the pocket brackets, a pair of arms projecting from the supporting bar, one at each end 15

In testimony whereof I affix my signature.
WADE H. HARRISON.
